FIG.3

FIG. 1 is a front elevational view of a television cart showing my new design;

FIG. 2 is a side elevational view taken at the right side of FIG. 1; and

FIG. 3 is a perspective view of the television cart showing the opposite side thereof.

The dominant features of my design reside in those portions shown in full lines on the drawings.

I claim:

The ornamental design for a television cart, substantially as shown and described.
